Des. 181,395

Patented Nov. 5, 1957

181,395

COMBINATION POPCORN MACHINE AND BEVERAGE DISPENSER

Samuel M. Waas, Kansas City, Mo., assignor to Manley,
Inc., Kansas City, Mo., a corporation of Missouri

Application April 16, 1956, Serial No. 41,077

Term of patent 14 years

(Cl. D81—10)

Fig. 2 is a rear perspective view of the combination popcorn machine and beverage dispenser.

The ends of the base section of the machine are identical in appearance.

I claim:

The ornamental design for a combination popcorn machine and beverage dispenser, as shown and described.
